INSTRUCTIONAL DEVICE ON THE OPERATION OF VOTING MACHINES

Carl R. Finegan, Elyria, Ohio

Application August 6, 1948, Serial No. 42,858

3 Claims. (Cl. 35—13)

1

My invention relates in general to a device for instructing voters in the use of a voting machine.

In the past few years many political subdivisions of the country have been installing voting machines in place of the old paper ballots. Since these voting machines are expensive and will register the vote of many voters there are relatively few of the machines as compared to the number of voters using them. Thus, the individual voter does not have an opportunity to spend much time learning to operate the machine. Generally the voter tries to learn how to operate the machine on the day of the election instead of making a special trip to the voting place before the election day. I have discovered that it is a great advantage to the public to have some means whereby the public may easily learn how to operate the voting machine before going to the poll or voting place. It is generally understood that to teach the public how to use the machine, the machine must be taken to the public since the voters will not go to the voting place to learn to operate the machine before election day.

Therefore, one of the objects of my invention is to provide an inexpensive instructional device which may be easily constructed in large quantities and distributed to the public.

Another object of my invention is to provide a voting machine instructional device comprising a keyboard representing a voting machine and having voting indicators operable the same as those on the regular voting machine.

Still another object of my invention is to provide a means for instructing a high percentage of the voters in the use of the voting machine without causing the voters to go to the place of voting.

Other objects and a fuller understanding of my invention may be had by referring to the following description and claims, taken in conjunction with the accompanying drawings, in which:

Figure 1 is a front elevational view of my instruction device representing the voting machine as it first appears to the voter;

Figure 2 is a back elevational view, the back cover having been removed, of the keyboard of my instruction device showing some of the indicators in the voted position with the curtain handle in its closed position and with some of the indicators in non-voted position;

Figure 3 is a sectional view along the line 3—3 of Figure 2; and

Figure 4 is a sectional view along the line 4—4 of Figure 2.

2

My voting machine instruction device comprises generally a keyboard 10 having a back side 11 and a face side 12. The keyboard 10 is supported by a housing 19 having a back cover 31, 5 which has been removed in Figure 2. The face side 12 is a representation of a voting machine used by the voter and thus includes party rows 13 and 14 respectively, of candidates' names. The party row 13 is illustrated as having candidates' names 15 and 16, while the party row 14 is illustrated as having candidates' names 17 and 18. It is understood that any number of candidates' names may be placed on my keyboard 10, and that I have placed two names for each party 10 by way of example only. The keyboard 10 has arcuate slots 20 next adjacent each of the candidates' names 15, 16, 17, 18 and 19. I have provided voting indicators 21, 22, 23 and 24 for each of the candidates' names 15 to 18, respectively. 15 These voting indicators 21 through 24 are pivotally mounted on the face side 12 of the keyboard 10 with each voting indicator next adjacent its respective candidate name. The voting indicators are pivotally mounted in rows substantially 20 by parallel to the party rows. Lever arms 25, 26, 25 and 28 are mounted on the back side 11 of the keyboard 10, and are aligned with their respective voting indicators 21 through 24 inclusive. In my drawings I have illustrated the 30 pivotal mounting of each lever arm with its respective voting indicator on opposite sides of the keyboard 10 by means of a rivet 29. Thus, each lever arm is pivoted about the same axis as each voting indicator. I have also connected each lever arm with its respective voting indicator by 35 a member 30 which extends through the respective arcuate slot 20 provided therefor. The voting indicators and their respective lever arms are thus annularly movable toward the respective candidate name to a voted position and 40 away from the respective candidate name to a non-voting position with the members 30 reciprocally moving in the respective slots 20. I have further provided my keyboard 10 with a curtain handle 32 and a control lever 33 fastened thereto 45 for angular movement therewith. The curtain handle 32 is pivotally mounted on the face side 12 while the control lever 33 is mounted on the back side 11. A rivet 34 extending through the curtain handle 32, the keyboard 10 and the control lever 33, pivotally mounts the handle 32 and 50 control lever 33 on the keyboard 10. An arcuate slot 35 is also provided next adjacent the curtain handle 32. A member 36 extending through the arcuate slot 35 connects the curtain handle 32 55 and the control lever 33 for angular movement

of the control lever 33 with movement of the curtain handle 32. I have connected the lever arms 25 through 28 of the voting indicators 21 through 24, respectively, to the control lever 33 by flexible connectors 40 to 43. The flexible connector 40 is fastened to the lever arm 25, the connector 41 to lever 26, the connector 42 to lever 27, and the connector 43 to the lever 28. When the curtain handle is moved annularly in one direction to a curtain closed position, these flexible connectors 40 through 43 are drawn tight and thus pull the voting indicators 21 through 24 respectively to the non-voted position. When the curtain handle is moved to the curtain closed position which symbolizes the closing of the curtain on the big voting machine, these flexible connectors 40 to 43 inclusive are relaxed, thus permitting annular movement of the voting indicators 21 to 24 to voting position. I have also provided the keyboard with party levers 44 and 45 for the respective party rows 13 and 14. These party levers 44 and 45 are pivotally supported by pivot support means 46 and 47, respectively and are in substantially longitudinal alignment with the voting indicators of their respective party row. Springs 48 and 49 connected between the housing 19 and the respective party levers 44 and 45 normally hold the party levers in a position as indicated in Figure 1 of the drawing. It is understood that other suitable means may be used in place of the springs 48 and 49 which will serve the same purpose. I have connected each of the party levers 44 and 45 to the voting indicators in its particular party row by means of flexible connectors 50 to 53, inclusive. The flexible connectors 50 and 51 connect the party lever 44 to the lever arms 25 and 26 of the voting indicators 21 and 22, respectively, while the flexible connectors 52 and 53 connect the party lever 45 to the lever arm 27 and 28 of the voting indicators 23 and 24, respectively. When the curtain handle 32 is in open curtain position as illustrated in Figure 1, the connectors for the party levers are taught. When the party levers are pivoted relative to the keyboard 10, the curtain handle 32 having been moved to closed curtain position, they pull all of the voting indicators in their particular party row into voting position. In Figure 2 of my drawings I have illustrated the back side of a keyboard with the curtain handle in closed curtain position, and with the voting indicators 25 and 27 in non-voting position. The voting indicators 25 and 28 are illustrated in voted position, thus indicating the voting of a split party ticket. Should the applicant desire to vote a straight party ticket he merely has to pivotally move the party lever for the party of his choice, which thus pulls all of the voting indicators in that party row into voted position. I have also provided my instruction device with a question and answer indicator as illustrated by the numbers 55 and 56 of Figure 1. In this instance the indicator 55, is labeled "yes" and the indicator 56 is labeled "no." These indicators 55 and 56 are substantially the same as the voting indicators and have levers 57 and 58 attached thereto in the same manner as the voting indicators. I have connected the levers 57 and 58 of the voting indicators 55 and 56 respectively, to the control lever 33 of the curtain handle 32 by flexible members 59 and 60, respectively. Should a bond issue or any similar "yes" and "no" vote be taken, the voter merely has to move the indicator "yes" or the indicator "no" to the voted position.

The instruction device is merely a form of

teaching the use of a voting machine and is operated in the same manner as the voting machine. The operator first moves the curtain handle to closed curtain position, thus loosening all of the flexible connectors fastened thereto. If the voter wishes to vote a straight ticket he merely has to move the party handle of his choice which moves all of the voting indicators in that party to voted position. Should the applicant wish to vote a split ticket he first votes a straight party ticket, then moves the voting indicators of the candidates he does not want in office to non-voting position and moves the voting indicators of the candidates of the other party he does want in office to voted position. After making all of his selections, the voter then moves the curtain handle to open curtain position, thus symbolizing the registering of his vote and opening of the curtain on a real voting machine.

Although the invention has been described with a certain degree of particularity in its preferred form, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

30 1. An instruction device for instructing a voter in the correct manipulation of a voting machine comprising, a keyboard having a back side and having a face side with a representation of a voting machine used by the voters and including party rows of candidate names for offices, a voting indicator for each name pivotally mounted on the face side of said keyboard for movement angularly toward its respective name to a voted position and for movement angularly away from its respective name to a non-voted position, levers having opposite ends on the back side of said keyboard one secured between the opposite ends thereof to each voting indicator for angular movement therewith, a party lever for each of the party rows pivotally mounted on said keyboard and in substantial longitudinal alignment with the voting indicators of its respective party row of candidates, first flexible connectors interconnecting each of said party levers and one end of each of the levers in its respective party row to move all of the voting indicators in that row into voted position upon pivotal movement of the party lever, a curtain handle pivotally mounted on the face side of said keyboard for movement angularly in one direction to an open curtain position and for movement angularly in the opposite direction to a closed curtain position, a control lever on the back side of said keyboard and secured to said curtain handle for angular movement therewith, and second flexible connectors interconnecting the other end of each of said levers and said control lever to angularly move its respective voting indicator to its non-voted position upon movement of the curtain handle to its open curtain position, thereby symbolizing the registering of a vote on a voting machine.

70 2. An instruction device for instructing a voter in the correct manipulation of a voting machine comprising, a keyboard having a back side and having a face side with a representation of a voting machine used by the voters and including party rows of candidate names for offices, a voting indicator for each name pivotally mounted on the face side of said keyboard for movement

angularly toward its respective name to a voted position and for movement angularly away from its respective name to a non-voted position, levers on the back side of said keyboard, one secured to each voting indicator for angular movement therewith, each lever having first and second connection points spaced apart from each other, a party lever for each of the party rows pivotally mounted on said keyboard and in substantial longitudinal alignment with the voting indicators of its respective party row of candidates, first flexible connectors interconnecting each of said party levers and the first connection point of the levers in its respective party row to move all of the voting indicators in that row into voted position upon pivotal movement of the party lever, a curtain handle pivotally mounted on the face side of said keyboard for movement angularly in one direction to an open curtain position and for movement angularly in the opposite direction to a closed curtain position, a control lever on the back side of said keyboard and secured to said curtain handle for angular movement therewith, and second flexible connectors interconnecting the second connection point of each of said levers and said control lever to angularly move its respective voting indicator to its voted position upon movement of the curtain handle to its open curtain position, thereby symbolizing the registering of a vote on a voting machine.

3. An instruction device for instructing a voter in the correct manipulation of a voting machine comprising, a keyboard having a face side with a representation of a voting machine used by the voters and including rows of candidate names for offices, voting indicator means for each name pivotally mounted on said keyboard for movement angularly in one direction to a voted position and

for movement angularly in the opposite direction to a non-voted position, each of said voting indicator means having first and second connection points, a row lever for each of the rows of candidate names pivotally mounted on said keyboard and in substantial longitudinal alignment with the voting indicator means of its respective row of candidates, first flexible connectors interconnecting each of said row levers and the first connection point of each of the voting indicator means of its respective row of candidate names to move all of the voting indicator means of that row into voted position upon pivotal movement of the respective row lever, curtain handle means pivotally mounted on said keyboard for movement in one direction to an open curtain position and for movement in an opposite direction to a closed curtain position, and second flexible connectors interconnecting said curtain handle means and the second connection point of each of said voting indicator means to angularly move the voting indicator means to non-voted position upon movement of the curtain handle to open curtain position, symbolizing the registering of a vote on the machine.
